CLAIM

The ornamental design for a display screen with a graphical user interface for taking photos in a recording, as shown and described.

DESCRIPTION

FIG. 1 is a front view of a display screen with a graphical user interface for taking photos in a recording showing our new design, and in particular, showing a first image thereof; FIG. 2 is a front view thereof showing a second image thereof;

FIG. 3 is a front view thereof showing a third image thereof; FIG. 4 is a front view thereof showing a fourth image thereof;

FIG. 5 is a front view thereof showing a fifth image thereof; FIG. 6 is a front view thereof showing a sixth image thereof; FIG. 7 is a front view thereof showing a seventh image thereof; and,

FIG. 8 is a front view thereof showing an eighth image thereof.

The broken lines depicting the characters and the contour of the display screen form no part of the claimed design.

The appearance of the transitional image sequentially transitions between the images shown in FIGS. 1-8. The process or period in which one image transitions to another image forms no part of the claimed design.
